Primary Examiner — Jennifer L. Watkins(74) *Attorney, Agent, or Firm* — Arash Behravesh; Mannava & Kang, P.C.(57) **CLAIM**

The ornamental design for a pocket portion of a scarf of a travel support structure, as shown and described.

DESCRIPTION

FIG. 1 is a front perspective view of the front side of a pocket portion of a scarf of a travel support structure in use arranged around a neck of a person showing a new design; FIG. 2 is a quarter turn perspective view thereof; and, FIG. 3 is a plan view of the back side in a flat position thereof.

In the drawings, the broken lines depict environmental subject matter only and form no part of the claimed design.
